UNITED STATES PATENT OFFICE.

WILLIAM LAWRENCE, OF WORCESTER, MASSACHUSETTS.

AMBULANCE.

SPECIFICATION forming part of Letters Patent No. 398,517, dated February 26, 1889.

Application filed November 3, 1888. Serial No. 289,934. (No model.)

To all whom it may concern:

Be it known that I, WILLIAM LAWRENCE, a citizen of the United States, residing at Worcester, in the county of Worcester and State of Massachusetts, have invented certain new and useful Improvements in Ambulances; and I do hereby declare that the following is a full, clear, and exact description thereof, which, in connection with the drawings making a part of this specification, will enable others skilled in the art to which my invention belongs to make and use the same.

My invention relates to ambulances for carrying the sick and wounded, and more particularly to the stretcher supported within the ambulance, and upon which the patient is placed.

The object of my invention is to so construct the stretcher and combine it with the ambulance-body that there shall be the least possible jar to the patient, and also to provide for the raising or lowering of the stretcher within the ambulance-body after the patient is placed thereon; and my invention consists in certain novel features of construction and operation of a hanging frame or sling in which the stretcher is supported and the combination of the same with the ambulance-body, as will be hereinafter fully described.

Referring to the drawings, Figure 1 is a side view, partially broken away, of an ambulance-wagon with my improvements applied thereto; and Fig. 2 is a rear end view, the back-board being down.

In the accompanying drawings, 1 represents an ambulance-wagon body of any ordinary construction, with inclosed sides and ends.

A stretcher, 2, of any ordinary construction, rests upon the bottom of the ambulance. A second stretcher, 3, to which my present invention relates, is supported above the stretcher 2.

The stretcher 3 consists of the base part or frame 4, upon which the mattress 5 rests, and the side poles, 6, and end poles, 7, which furnish means for carrying the stretcher, said poles being secured on posts 7', extending up from frame 4. The stretcher 3, when in position in the ambulance-body, rests and is supported upon a sling or hanging frame, 8, which consists of a base, 9, suspended by means of

vertical springs 10, two or more on each side, (four being shown in the drawings,) from cross-pieces 11, which cross-pieces are in turn suspended by means of cords or flat bands 12 from pulleys 13, which are fast upon a shaft, 14, extending centrally in this instance, in the upper part of the ambulance-body, and supported to turn in bearings at the ends of brackets 15. The outer end, 14', of the shaft 14 is made square, adapted for engagement with a wrench to turn the shaft in either direction to raise or lower the cross-pieces 11, and with them the frame 8, upon which the stretcher 3 is supported.

A ratchet-wheel, 16, is secured on the end 14' of the shaft 14, and a catch-over pawl, 17, pivoted above and adapted to fit over the teeth of the ratchet-wheel and hold the shaft 14 and the frame 8 suspended therefrom at the desired height.

In order to prevent too much motion or swinging of the cross-pieces 11, after the frame 8 is drawn up into position, cords 18 are provided, secured at their upper ends to the ambulance-body, and having hooks at their lower ends adapted to catch into eyes 11' in the cross-pieces 11.

The use of the cords 18 may be dispensed with and other equivalent means provided.

Spiral springs 19, two or more on each side, are secured at one end to the sides of the frame 8 and extend at right angles to the vertical springs 10. The outer ends of said springs 19 are in this instance provided with eyes 19', which encircle and slide freely up and down on the side rods, 20, secured at the sides of the ambulance-body, (see Fig. 2,) so that when the frame 8, with the stretcher 3 supported thereon, is raised or lowered the side springs, 19, will move up and down with it, and thus always remain in the same position relatively to the springs 10.

The purpose of the side springs, 19, is to overcome any side jar or jolt of the ambulance-body and to allow the frame 8 and stretcher 3 thereon to have a yielding side or horizontal motion, as well as a yielding vertical motion, thus doing away with any jar to the patient.

I have shown the shaft 14, by means of which the frame 8 and stretcher 3 thereon are

raised and lowered, at the top of the ambulance-body; but it may equally well be placed at one side of the ambulance-body or near the bottom thereof, and the bands or cords 12 pass over pulleys arranged at the top and also at one side of the ambulance-body to said shaft.

From the above description, in connection with the drawings, the operation of my invention will be readily understood by those skilled in the art, and briefly is as follows: The several parts being in the position shown in the drawings, the pawl 16 is disconnected from the ratchet-wheel 15, allowing the shaft 14 to turn and the frame 8 and stretcher 3 thereon to be lowered until said frame rests upon the lower stretcher, 2, or the bottom of the ambulance-body in case the stretcher 2 is removed. The stretcher 3 is then drawn out of the frame by means of the poles 6 and 7. After the patient is placed upon the mattress 5 of the stretcher 3 said stretcher is pushed into the sling or frame 8. Said frame is then raised up into the position shown in the drawings by means of a wrench on the end 14' of the shaft 14, and in case it is desired to carry a second patient at the same time the stretcher 2 is placed upon the bottom of the ambulance-body under the swinging frame 8.

I have shown and described my invention applied to an ambulance-wagon; but it may 30 equally well be applied to other kinds of conveyances.

Having thus described my invention, what I claim as new, and desire to secure by Letters Patent, is—

35

1. In an ambulance, the combination, with the stretcher-frame supported by vertical spiral springs and attached to lateral horizontal spiral springs, of means for raising and lowering said frame and holding the same in 40 place, substantially as shown and described.

2. In an ambulance, the combination, with the hanging stretcher-frame, consisting of the base 9, spiral springs 10, and cross-pieces 11, and the horizontal spiral springs 19, attached 45 to said frame, of means for raising and lowering said frame, consisting of a shaft supported and turning in bearings within the ambulance-body, and straps or cords connecting the cross-pieces 11 with said shaft, substan- 50 tially as shown and described.

WILLIAM LAWRENCE.
